UNITED STATES PATENT OFFICE

EARL R. SWANSON, OF CHICAGO, ILLINOIS, ASSIGNOR TO CHICAGO-CLEVELAND CAR ROOFING COMPANY, OF CHICAGO, ILLINOIS, A CORPORATION OF DELAWARE

RAILWAY CAR

Application filed July 31, 1930. Serial No. 472,166.

My invention relates to railway cars and more particularly to load lifting devices associated with the roofs of railway cars of the box type.

5 The principal object of the invention is to provide a railway car with means which, in addition to serving as a load lifting device, is designed to perform the usual functions of a ridge pole by reinforcing and bracing the 10 car roof and by affording a support for the roof sheets.

A primary feature of the invention consists in providing a car roof having carlines disposed below and projecting downwardly 15 from the roof sheets with a beam extending longitudinally of the car between the carlines and rigidly secured to the latter, the beam being provided with transversely extending members forming therewith structures of 20 box-like section and adapted to serve as supports for load lifting means.

Another feature of the invention is to provide, in combination, carlines of substantially 25 channel-shape having webs and upwardly extending legs, a roof sheet spanning the space between the carlines and a beam extending longitudinally of the car between the carlines and affording a support for the roof sheet, members being secured to the beam 30 forming therewith structures of box-like section and constituting means for supporting load lifting devices.

A further feature of the invention consists 35 in providing the carlines with oppositely disposed, laterally extending flanges secured to the undersides of adjacent roof sheets and in associating therewith a beam extending longitudinally of the car between the carlines and secured to adjacent flanges of the latter, 40 the beam being provided with members extending transversely of the car intermediate the carlines forming with the beam structures of box-like section and adapted to serve as supports for load lifting devices.

45 A still further feature of the invention consists in providing the car roof with a plurality of carlines disposed below and projecting downwardly from the roof sheets, a plurality of longitudinally extending beams respectively disposed on opposite sides of the carlines

and rigidly secured thereto, each of the beams being in supporting engagement with the undersides of adjacent roof sheets and being provided with means adapted to serve as supports for load lifting devices.

55 Other and more specific features of the invention residing in advantageous forms, combinations and relations of parts will hereinafter appear and be pointed out in the claims.

60 In the drawings illustrating a preferred embodiment of the invention,—

Figure 1 is a longitudinal sectional view of 65 a roof of a railway box car showing the invention applied thereto.

Figure 2 is a fragmentary transverse sectional view taken on line 2—2, Figure 1.

Figure 3 is an enlarged sectional view taken 70 on line 3—3, Figure 1.

Figure 4 is an enlarged sectional view taken 75 on line 4—4, Figure 1.

Referring more particularly to the drawings, 1 and 2 respectively designate the rigidly connected side and end plates of the car. Extending transversely of the car are substantially channel-shaped carlines, each of 80 which is provided with a web 3, upwardly extending legs 4 and oppositely disposed laterally extending flanges 5. The carlines may advantageously decrease progressively in depth from adjacent the ridge to the eaves of the roof and at their ends they are flanged downwardly as at 6 for attachment to adjacent portions of the side plates 1.

85 Spanning the spaces between the carlines and between the end plates and adjacent carlines are roof sheets 7. The end roof sheets, that is the sheets adjacent the end plates, are flanged downwardly as at 8 for attachment to the latter by rivets 9. The other roof sheets, 90 together with the opposite side edges of the end roof sheets, are overlappingly secured by rivets 10 to the lateral flanges 5 of the carlines and as may be seen in Figure 1 the roof sheets are arranged so that one sheet of the two which are adjacent each carline bridges or closes the channel portion of the latter.

95 Extending longitudinally of the car and respectively disposed on opposite sides of the carlines are beams 11. Each of these beams 100

is of inverted channel-shape having a web 12 and downwardly extending legs 13 which terminate in oppositely disposed laterally projecting flanges 14. To connect the beams adjacent the ends of the car to the end plates, angularly shaped brackets 15 may be conveniently employed. Each of these brackets is formed with a substantially vertical flange 16 for attachment by rivets 17 to the adjacent end plate and with a substantially horizontal flange 18 for attachment by rivets 19 to the laterally extending flanges 14 of the beam. The opposite end of each of the beams which adjoin the end plate are rigidly secured to the adjacent flange 5 of the neighboring car-line by one of the roof sheet attaching rivets 10, the rivet passing through the web 12 of the beam. Each of the other beams with which the roof is provided is secured to the car-lines in a similar manner. In order that the beams may serve to support portions of the roof sheets between the car-lines, the portions of the webs of the beams which extend under and are secured to the lateral flanges 5 of the car-lines are offset downwardly as at 20. In this manner the upper surface of the webs of the beams are disposed in supporting engagement with the undersides of the major portions of the roof sheets. To produce a more rigid construction intermediate portions of the roof sheets may be connected by rivets 21 to the webs of the beams.

Associated with each of the beams is a plurality of transversely extending members 22. Each of these members is secured to the lateral flanges 14 of its associated beam by rivets 23 thereby forming with the beam a structure of box-like section. While the members 22 may be of any convenient or desired shape, it is preferred to form each of them with a substantially horizontal plate portion 24 and with downwardly extending side marginal flanges 25. The plate portion of each member is spaced from the web 12 of the associated beam a sufficient distance to permit a rope, chain, nose of a hook or any other suitable means capable of supporting a load lifting device to be inserted in the space or opening defined by the plate portion 23 and the web 21. Thus simple and rigid means are provided whereby a load lifting device may be conveniently supported adjacent the car roof for moving automobiles or other heavy structures into and out of the car or for raising them within the car to permit a platform rack or any desired support to be placed under them for shipment.

From the foregoing it will be perceived that the beams as well as their attachments are disposed considerably above the lower edges of the car-lines which project downwardly from the roof sheets so that they do not interfere with the loading of lading within the car. Furthermore, the beams are so arranged that they adequately brace and re-

inforce the roof structure and also support the roof sheets.

I claim:

1. A roof for railway cars involving roof sheets, car-lines disposed beneath said roof sheets and projecting downwardly therefrom, a beam extending longitudinally of the car between said car-lines and above the lower edges of the latter, said beam being of inverted channel shape and being rigidly secured to said car-lines, and a member extending transversely of and rigidly secured to said beam, said member forming with the beam a structure of box-like section and being adapted to serve as a support for a load lifting means. 70

2. A roof for railway cars involving roof sheets, car-lines disposed below and projecting downwardly from the roof sheets, a beam extending longitudinally of the car between said car-lines and above the lower edges of the latter, said beam being rigidly secured to the car-lines and being of inverted channel shape having oppositely disposed laterally projecting flanges, and a member extending transversely of said beam and rigidly secured to the flanges thereof, said member forming with the beam a structure of box-like section and being adapted to serve as a support for a load lifting means. 80

3. A roof for railway cars involving roof sheets, car-lines disposed beneath said sheets and projecting downwardly therefrom, each of said car-lines having a web and upwardly extending legs, a beam extending longitudinally of the car between said car-lines above the lower edges of the latter, said beam being of inverted channel shape and being rigidly secured to said car-lines, and a member extending transversely of and rigidly secured to said beam, said member forming with the beam a structure of box-like section and being adapted to serve as a support for a load lifting means. 100

4. A roof for railway cars involving roof sheets, car-lines disposed below and projecting downwardly from the roof sheets, each of said car-lines having a web and upwardly extending legs terminating in lateral flanges, said flanges being secured to the undersides of the roof sheets, and a beam extending longitudinally of the car between said car-lines above the lower edges of the latter, said beam being of inverted channel shape and being connected to said car-lines, and a member extending transversely of and rigidly secured to said beam, the said member forming with the beam a structure of box-like section and being adapted to serve as a support for a load lifting device. 110

5. A roof for railway cars involving a plurality of roof sheets, car-lines disposed beneath and projecting downwardly from said roof sheets, each of said car-lines having a web and upwardly extending legs terminat- 125

ing in oppositely disposed laterally projecting flanges, a beam of inverted channel shape extending longitudinally of the car between said carlines and rigidly secured to the car-
5 line flanges adjacent thereto, and a member extending transversely of and rigidly secured to said beam, said member forming with the beam a structure of box-like section and being adapted to serve as a support for a load
10 lifting means.

6. A roof for railway cars involving roof sheets, carlines disposed below and projecting downwardly from the roof sheets, each of said carlines being of substantially chan-
15 nel shape and having oppositely projecting flanges rigidly secured to the roof sheets, a beam of inverted channel shape extending longitudinally of the car between the carlines and rigidly secured to the carline flanges adjacent thereto, said beam being provided with laterally extending flanges and having means rigidly secured to the latter intermediate said carlines, said means forming with the beam a structure of box-like section and
20 being adapted to serve as a support for a load lifting means.

7. A roof for railway cars comprising a plurality of carlines each of which is provided with a web and upwardly extending
30 legs, the legs of each carline terminating in oppositely disposed laterally projecting flanges, a roof sheet spanning the space between said carlines and overlappingly secured to the flanges of the latter, a beam ex-
35 tending longitudinally of the car between the carlines in supporting engagement with the underside of said roof sheet, said beam being of inverted channel shape and rigidly secured to the carline flanges adjacent thereto,
40 and a member extending transversely of the beam and rigidly secured thereto intermediate said carlines, said member forming with the beam a structure of box-like section and being adapted to serve as a support for a
45 load lifting means.

8. A roof for railway cars involving a plurality of carlines, each of said carlines having a web and upwardly extending legs terminating in oppositely disposed laterally
50 projecting flanges, a roof sheet spanning the space between said carlines and rigidly secured to the flanges of the latter, a beam of inverted channel shape extending between said carlines below the roof sheet, said beam
55 being rigidly secured to the carline flanges adjacent thereto and to the said roof sheet, and a member extending transversely of the beam and rigidly secured thereto intermediate the carlines, said member forming with
60 the beam a structure of box-like section and being adapted to serve as a support for a load lifting means.

9. A roof for railway cars involving a plurality of carlines, each of said carlines being provided with a web and upwardly extend-

ing legs terminating in laterally projecting flanges, a roof sheet spanning the space between said carlines and overlappingly secured to the flanges of the latter, a beam of inverted channel shape extending longitudinally of the car between said carlines, said beam having a web rigidly secured to the car-
70 line flanges adjacent thereto and to the underside of said roof sheet, and a member ex-
75 tends transversely of the beam and rigidly secured thereto intermediate the carlines, said member forming with the beam a struc-
ture of box-like section and being adapted to serve as a support for a load lifting means.

10. A roof for railway cars involving a plurality of roof sheets, carlines disposed beneath said sheets and projecting downwardly therefrom, a plurality of beams ex-
80 tending longitudinally of the car and re-
spectively disposed on opposite sides of said carlines, each of said beams being of in-
85 vided channel shape and being rigidly secured to the carlines adjacent thereto, and a plurality of members extending transversely of the car and rigidly secured to said beams,
90 each of said members forming with its as-
sociated beam a structure of box-like section and being adapted to serve as a support for a load lifting device.

In testimony whereof I affix my signature. 95
